JOHN H. IRWIN, OF CHICAGO, ILLINOIS.

Letters Patent No. 66,153, dated June 25, 1867.

IMPROVEMENT IN APPARATUS FOR CARBURETTING AIR.

The Schedule referred to in these Letters Patent and making part of the same.

TO ALL WHOM IT MAY CONCERN:

Be it known that I, JOHN H. IRWIN, of the city of Chicago, in the county of Cook, and State of Illinois, have invented a new and useful Improvement in Apparatus for Carburetting Air for illuminating purposes; and I do hereby declare and make known that the following is a full, clear, and exact description of the same, reference being had to the drawings accompanying, and the letters and figures marked thereon, which form part of this specification.

This invention relates to the application of the principles set forth in the patent granted to me on the eleventh day of April, in the year of our Lord one thousand eight hundred and sixty-five, for chandeliers, side lights, and movable lights or lamps, to enable the said invention to be used without the expense of laying gas-pipes through the house.

To enable those skilled in the art to understand how to construct and use my invention, I will proceed to describe the same with particularity, making reference to the aforesaid drawings, in which—

Figure 1 represents a side elevation of my invention as applied to a pendent chandelier

Figure 2 is an enlarged vertical section of the same.

Figure 3 represents the same invention as applied to side light.

Figure 4 is the same in the form of a portable lamp.

Figure 5 is a plan or top view of fig. 2 in section at *x*; and

Figure 6 represents a vertical section of a lamp embodying my invention, as hereinafter described.

The same letters of reference in the different figures denote the same parts of my invention.

A represents a case enclosing a carburetted vessel, *D*, which is arranged within said case substantially as shown. *B* represents an annular pipe, as shown in figs. 1 and 2, in which the gas or carburetted air descends to the burners, there being a central tube within said pipe through which the rod *b* passes, as shown, said rod being firmly secured to the ceiling, as represented, or in any other convenient manner. *A'* represents a rim extending around the casing *A*, so that the apparatus may thoroughly conceal the arrangement for securing the same to the ceiling. *C* represent tubes connecting the smoke bells over the burners with the case *A* around the carburetter, and constitute the inlet for air into the same, it passing from the case into the carburetter through the perforations *O*, as shown. The carburetter, as seen in fig. 5, is constructed with two chambers, so as to use fluid of different degrees of specific gravity, the filling being done alternately in the different chambers through the openings *a a*. The atmospheric current, however, passes through both chambers, passing through an opening in the upper part of the wall separating the chambers marked *a'*, as shown, and thence down through the annular pipe *B* to the burners. The effect of the heat passing up through the tubes *C* is twofold, serving, as it does, to warm the carburetter and facilitate the vaporization of the contents, and also by the force of the ascending column of heated air communicating with the carburetter through *o* to produce additional pressure at the burners. In figs. 1 and 2 the vessel containing the vaporizing fluid lies close against the ceiling, as shown, and may be made in ornamental designs, so as to add to the appearance of the room very greatly. By removing the nut *d* upon the lower end of the rod *b* it is readily seen that the entire apparatus is lowered for convenience in filling or other purposes, and raised again to place and secured by simply replacing the nut *d*. In fig. 3 the invention is represented as used for a side light, the same being suspended upon a hook, as shown, the carburetter being provided with some suitable inlet for air, as the tube *C* does not open into the case *A*, but the heated air escapes through the apertures *e e* directly beneath it. The tube *C* may, however, open into the case, if desired, in this as in all other forms of applying this principle. Fig. 4 represents a portable lamp, which is readily seen to embody the same features. Fig. 6 represents a lamp in which two separate carburetters are combined, one for containing the heavier hydrocarbons, which vaporize upon the application of heat, and an auxiliary one to contain naphtha to be used in starting the light, *E* representing the said auxiliary carburetter. The heavy fluid is placed in the upper vessel *D* and the naphtha into the smaller one marked *E*, which is wholly disconnected from *D*, and which is provided with a cock, *p*, by which air may be admitted into or excluded from the same. To light up this lamp the cock *p* is turned to admit air into the naphtha vessel *E*, which, being readily carburetted, falls down to the burners through an opening, *m*, in the pipe. The combustion thus produced heats up the case surrounding the larger reservoir *D*, containing the heavy fluid, and the heated

air enters the same, and thus, by the effect of the heat thus produced, the apparatus operates automatically and the cock p is turned to exclude the air from E , which is only used to start the apparatus. n represent devices for drawing off any residuum, and also serve as gauges to regulate the amount of fluid in the vessels, as but a small quantity should be used at a time, and the tubes n rise as far into the carburetter as it is desired that the carburetter should be filled, and when the fluid flows through said tubes n the filling should cease and the cocks be closed.

Having described my invention, I will now specify what I claim, and desire to secure by Letters Patent:

1. I claim the combination of a carburetting device with a chandelier bracket or a portable lamp, when arranged and operating substantially as described.
2. I claim, in combination with a chandelier bracket or portable lamp, two carburetting vessels to contain two different grades of hydrocarbon oil, substantially as and for the purposes specified.

J. H. IRWIN.
